UNITED STATES PATENT OFFICE.

CARL KANEV, OF PHILADELPHIA, PENNSYLVANIA.

DESIGN FOR A GEAR-COVER.

59,358.

Specification for Design.

Patented Oct. 11, 1921.

Application filed June 1, 1921. Serial No. 474,278. Term of patent 7 years.

To all whom it may concern:

Be it known that I, CARL KANEV, a citizen of the United States, residing at Philadelphia, in the county of Philadelphia and State of Pennsylvania, have invented a new, original, and ornamental Design for a Gear-Cover, of which the following is a specification, reference being had to the accompanying drawing, forming a part thereof, in which—

Figure 1 is an outer face view of a gear cover, showing my new design,

Fig. 2 is a view of the right hand side of Fig. 1,

Fig. 3 is a view of the reverse side of the cover from that shown in Fig. 1, and

Fig. 4 is a view of the right hand side of Fig. 3.

I claim:

The ornamental design for a gear cover, as shown.

CARL KANEV.
